DESIGN FOR A KETTLE

Gordon H. Brown, Detroit, Mich., assignor to Marian S. Brown, Detroit, Mich.

Application October 9, 1944, Serial No. 115,691

Term of patent 14 years

(Cl. D44—25)

To all whom it may concern:

Be it known that Gordon H. Brown, a citizen of the United States of America and a resident of Detroit, in the county of Wayne and State of Michigan, has invented a certain new, original, and ornamental Design for Kettle, of which the following is a specification, reference being had to the accompanying drawing, forming a part thereof and wherein:

Fig. 1 is a side elevational view of a kettle embodying my design;

Fig. 2 is a plan view of the same;
Fig. 3 is a front elevational view of the same;
and

Fig. 4 is a rear elevational view of the same.

I claim:

The ornamental design for a kettle, substantially as shown.

GORDON H. BROWN,
